UNITED STATES PATENT OFFICE.

WILLIAM WITTE, OF NEW HAVEN, CONNECTICUT.

BENT BOX.

SPECIFICATION forming part of Letters Patent No. 268,444, dated December 5, 1882.

Application filed October 9, 1882. (No model.)

To all whom it may concern:

Be it known that I, WILLIAM WITTE, a citizen of the United States, residing at New Haven, in the county of New Haven and State of Connecticut, have invented a new and useful Improvement in Bent Boxes, of which the following is a specification.

My invention relates to that class of paper boxes known as "knock-down" boxes; and it consists in certain features of construction, hereinafter described, and specifically set forth in the claims.

Referring to the drawings, Figure 1 is a plan of the blank, which, when properly folded, forms a box embodying my invention. Fig. 2 represents the first step in folding the blank, the outside thereof being shown with surface-shading. Fig. 3 represents the box complete and in a nearly flat or knock-down condition; and Fig. 4, a perspective of the box with one end closed.

Like letters indicate like parts in all the figures.

I take a piece of card-board, pasteboard, or other suitable material and cut it to the shape shown in Fig. 1, and score it in longitudinal and transverse lines, as indicated by dotted lines in said figure, thus producing the sections A, B, C, D, E, and F, having respectively the end covering-flaps *a c d e*, and the tucking-flaps *d'*, the sections B and F being without such flaps, as shown.

The edges *b* of section B may be straight, if desired; but I prefer to curve them slightly inward, as shown, for a purpose hereinafter specified.

By referring to Fig. 2, it will be seen that when section A is folded upon section B there are four contiguous body-forming sections, which have end covering-flaps, *a c d e*, the sections being first a double-fly section, formed of the two indicated by A and B, and the remaining sections being C, D, and E, while the section F is utilized as the seam or joining section of the body, which, for the purpose of giving a smooth finished exterior, is secured by paste or otherwise, if desired, to the inner surface of the double-fly section.

Thus far a box is produced which is adapted to lie flat, and having one of its sides of

double thickness of material, which are at their contiguous surfaces unattached to each other, so that when raised from a flat condition each of its ends may be closed by folding inwardly at right angles to the sides, the end flaps, *a c e* or *a e c*, in the order named, and finally the flap *d*. The tucking-flap *d'* may now be inserted between the flies A B, to serve as a means of retaining the end flaps in a closed condition. Cutting the edges of section B on curved lines, or on any lines which expose a portion of the contiguous surface of the section A below the scored or hinged line of the flap *a*, facilitates the insertion of the tucking-flap *d'*; but by slightly compressing the double-fly side the flies may be separated, so that when the edges *b* are straight the insertion of the tucking-flap is in no wise a difficult operation.

The order of folding the end flaps may be changed without restriction, except that the flap *d* shall be the last to be folded down.

It is apparent that the sections A B and the section F may be arranged at either end of the blank, so long as they are opposite ends thereof, and that the principle involved in my construction—the comprising of two flies of material in one wall or side—will permit of a variation in the location of that section. As, for example, it may constitute one of the narrower sides of the box, in which case the opposite narrower side covering-flap would be provided with a tucking-flap, the equivalent of *d'*.

Having now described my invention and its operation, what I claim as new, and desire to secure by Letters Patent, is—

1. The blank herein shown and described, consisting of the sections A, B, C, D, E, and F, the end flaps, *a c d e*, and the tucking-flaps *d'*, the flaps *a c* being separated by a flapless section, and the remaining end flaps being contiguous to each other in the order named.

2. A box-blank having six sections arranged in one row, as follows: an end section, A, provided with flaps, a single flapless section adjoining said section A, three adjoining sections, C D E, provided with flaps, and the joining or lap section F, all to constitute a box, substantially as described.

3. The box herein shown and described, con-

100

sisting of six contiguous sections arranged in one row and having the sides C D E united to the side folds of a lined or double side, A B, by a seam or lap-section, F, and provided with the covering-flaps *a c d e* and tucking-flaps *d'*, whereby both tucking-flaps are equally secured between the sections of the double

side, and access to the contents of the box can be obtained from either end without tearing the flaps.

WILLIAM WITTE.
